UNITED STATES PATENT OFFICE.

EDWIN E. SLICK, OF PITTSBURGH, PENNSYLVANIA.

METHOD OF ROLLING FLANGED SHAPES.

1,086,789.

Specification of Letters Patent.

Patented Feb. 10, 1914.

Application filed September 28, 1908. Serial No. 455,051.

To all whom it may concern:

Be it known that I, EDWIN E. SLICK, of Pittsburgh, Allegheny county, Pennsylvania, have invented a new and useful 5 Method of Rolling Flanged Shapes, of which the following is a full, clear, and exact description, reference being had to the accompanying drawings, forming part of this specification, in which—

10 Figure 1 is a longitudinal side elevation of a three-high stand of rolls showing the roughing roll passes; Fig. 2 is a similar view of the second stand of rolls showing the succeeding passes, in which the blanks are 15 further reduced; Fig. 3 is a longitudinal side elevation of a set of two-high rolls showing in duplicate the final pass arranged for finishing the shapes in the operation of rolling tie-plates; Fig. 4 is a view similar to 20 that of Fig. 2 showing the reducing passes as arranged in rolling the shape shown by Fig. 5; Fig. 5 is a view similar to that shown by Fig. 3 showing the finishing pass in duplicate as arranged to finish a modified 25 shape; and Figs. 6 and 7 are detail sectional end views showing a modified shape before and after being passed through the final finishing operation of my improved method.

30 My invention relates to the rolling of flanged shapes, and is designed to produce shapes having wide flanges without the use of universal mills having horizontal and vertical rolls.

35 In the drawings, Fig. 1 shows a three-high rolling mill having rolls 2, 3 and 4 and containing five passes. The rolling operation is started with a bloom or billet, which in passing through the first pass *a*, is provided with the rudimentary flange portions 40 5, 6, 7 and 8. The metal is then returned through the pass *b*, in which the flange portions 5, 6, 7 and 8 and connecting web portion 9 are elongated and further reduced in 45 area. The metal is then successively passed through the passes *c*, *d* and *e*. In these passes, the blank is elongated and the cross-sectional area of the various parts is reduced, and it will be noted that in the first 50 pass the flange portions 6 and 8 are in live grooves, and the flange portions 5 and 7 in dead grooves, while in the next pass *b* the flange portions 5 and 7 are in live grooves with the flange portions 6 and 8 in dead 55 grooves. The flange portions 5, 7 and portions 6, 8 located on opposite sides of the

two edges of the connecting web portion 9 are alternately in live grooves and dead grooves during the rolling operation, both in the passes in this and the succeeding sets 60 of rolls. The blank on leaving the pass *e* is then rolled and further reduced in the pass *f* located in the stand of rolls formed by the rolls 10, 11 and 12, as shown in Fig. 2. In this pass the blank is further reduced. The 65 blank is next within the pass *g* formed by the rolls 11 and 12, in which the two flange portions 6 and 8 are bent outwardly, and in which all of the flange portions are further reduced and elongated. The blank is then 70 passed through the pass *h*, in which the width of the web portion of the blank between the flanges is increased and the web portion of the blank is bent so as to bring the inner faces of the flange portions 5 and 75 7 on the upper side of the blank into substantially parallel vertical planes, the web adjacent to the flange portion being bent to form an acute angle with the inner faces of the flanges 5 and 7. The blank is next 80 passed through the pass *j* formed by the finishing rolls 13 and 14, as shown in Fig. 3. In this pass the upwardly projected flange portions are bent so as to bring their ends inwardly and downwardly toward each 85 other and toward the web of the shape preferably into curved form so as to form the lugs on the tie-plate being made by this rolling operation. The web portion of the blank is also straightened by this operation, 90 and the downwardly extending flange portions 6 and 8 are forced outwardly so as to extend in substantially the same plane as the web portion 9 of the blank. A duplicate 95 pass *j'* is provided in the rolls 13 and 14, the purpose of this pass being to increase the life of the rolls and reduce the number of roll changes necessary in rolling such shapes.

In rolling the modified shape as shown by Figs. 4 and 5, the reducing operation is first 100 carried out in the same manner as is shown in Fig. 1. The blank after being reduced in the pass *e* of Fig. 1, is then further reduced in the passes formed by the rolls 15, 16 and 17, as shown in Fig. 4. The blank after being passed through the pass *e* of Fig. 1 is then further reduced in the pass *f'* formed by the rolls 15 and 16 of Fig. 4, and is successively passed through the later 110 passes *g'* and *h'*. In these passes the blank is further reduced and shaped, the downwardly extending flanges 6 and 8 being bent

outwardly in the pass g' , and the web portion being bent in the pass h' so as to bring the inner faces of the flanges 5 and 7 in substantially parallel relation with each other. After the blank has been passed through the pass h' of Fig. 4, it is further shaped in one or the other of the passes k or k' , formed in the rolls 18 and 19 as shown in Fig. 5. In this last pass, the flanges 6 and 8 are bent outwardly so as to extend in substantially the same plane as the web portion 9 of the shape, and the flanges 5 and 7 are caused to project substantially perpendicular to the surface of the web and the outwardly extending flanges 6 and 8.

It will be noted that in the passes shown in Fig. 1 of the drawings, and the pass f or f' of Figs. 2 and 4, I show a shape of substantially I-beam form, that is, having flanges which extend on opposite sides on each edge of the web portion of the shape. In later passes, two of the flanges on one side of the web portion are bent outwardly so as to extend substantially parallel with the web portion of the blank, as shown in the passes j and k , in which the inner surface of the flanges 6 and 8 are bent outwardly and upwardly so as to be in the same plane with the lower surface of the web portion 9.

In Fig. 6 a preliminary form of shape is shown having a flange 7^a projecting from one edge of the web 9^a , the other flange 8^a being bent upwardly and the form of the shape shown in Fig. 6 is put through a later pass or passes in which the flange 8^a is bent outwardly into the plane of the web 9^a as is shown in Fig. 7.

The advantages of my invention result from the obtaining of shapes having wide flanges and projections extending on opposite sides of the flanges by means of ordinary mills other than universal mills, having horizontal and vertical rolls. By first 40 rolling the shape into substantially I-beam form and by then bending some of the flanges so formed outwardly into substantially the same plane as the web portion of the blank, I am enabled to form shapes having flanges of a width and thickness which have hitherto been considered impossible to roll in the ordinary mill having fixed passes.

It will be noted that during the bending operations, the web of the blank is supported 55 at all times, in this way preventing buckling or distortion of the web and insuring a good product.

While I have shown a preferred method and set of passes for forming the I-beam 60 section preliminary to bending the same into the desired form, it will be understood that the I-beam form may be rolled in any desirable way. It will also be understood that in some cases, the intermediate shape may 65 be of general T-form with flanges at one

edge only of the web, or of other form having oppositely projecting flanges. In this case, one flange would be bent toward the plane of the web, thus forming a section with one flange projecting therefrom near this edge. By the words "I-beam shape" in the claims, therefore, I do not intend to limit myself to the commercial I-beam form. I claim:

1. The method of rolling flanged shapes 75 consisting in taking a heated blank having oppositely extending flanges along at least one marginal edge of an integral web portion, and passing said blank through the passes of a rolling mill to further shape the blank, bending the web into planes at an oblique angle to each other and the flanges on one side of said web portion each into substantially the plane of the adjoining bent portion of the web in some of said passes, reducing the area of the blank in at least one later pass and then straightening the bent web of the blank in other of the passes to thereby bring the web and flange portions on one side of the web into the same plane. 80

2. The method of rolling flanged shapes 90 consisting in taking a heated blank having oppositely extending flanges on the marginal edges of an integral web portion and passing said blank through the passes of a rolling mill to further shape the blank, bending the web into planes at an oblique angle to each other, and the flanges on one side of the web each into substantially the same plane as the adjoining bent portion 95 of the web, reducing the area of the blank in at least one later pass and then straightening the web of the blank in other of the passes to thereby bring the bent web portions and flanges on one side of the web into 100 the same plane. 105

3. The method of rolling flanged shapes 110 consisting in taking a heated blank having oppositely extending flanges along at least one marginal edge of an integral web portion, and passing said blank through the passes of a rolling mill to further shape the blank, bending the web into planes at an oblique angle to each other and the flanges on one side of said web portion each into substantially the plane of the adjoining bent portion of the web in some of said passes, then further shaping and lessening the height of the flanges on the opposite side of the web while reducing the area of the shape 115 in at least one later pass and then straightening the bent web in other of the passes to thereby bring the web and the flanges on one side thereof into the same plane. 120

4. The method of rolling flanged shapes 125 consisting in taking a heated blank having oppositely extending flanges on the marginal edges of an integral web portion and passing said blank through the passes of a rolling mill to further shape the blank, bending the 130

web into planes at an oblique angle to each other and the flanges on one side of the web each into substantially the same plane as the adjoining bent portion of the web, then further shaping and lessening the height of the flanges on the opposite side of the web while reducing the area of the shape in at least one later pass, and then straightening the bent web in other of the passes to thereby bring the web and flanges on one side thereof into the same plane.

5. The method of rolling flanged shapes consisting in taking a heated blank having oppositely extending flanges along at least one marginal edge of an integral web portion, and passing said blank through the passes of a rolling mill to further shape the blank, bending the web into planes at an oblique angle to each other and the flanges 15 on one side of said web portion each into substantially the plane of the adjoining bent portion of the web in some of said passes, then lessening the height of the flanges on the opposite side of the web while reducing 20 the area of the shape in at least one later pass and then straightening the bent web and bending the flanges on one side of the web inwardly in other of the passes to thereby bring the web and flanges on one side 25 thereof into the same plane and bend the flanges on the opposite side of the web into hook form.

6. The method of rolling flanged shapes consisting in taking a heated blank having oppositely extending flanges on the marginal edges of an integral web portion and passing said blank through the passes of a rolling mill to further shape the blank, bending the web into planes at an oblique angle 30 to each other and the flanges on one side of the web each into substantially the same plane as the adjoining bent portion of the web, then lessening the height of the flanges on the opposite side of the web while reducing 35 the area of the shape in at least one later pass and then straightening the bent web and bending the flanges on one side of the web inwardly in other of the passes to thereby bring the web and flanges on one side 40 thereof into the same plane and bend the flanges on the opposite side of the web into hook form.

7. The method of rolling flanged shapes consisting in taking a heated blank having 45 oppositely extending flanges along the marginal edges of a connecting web portion and passing the blank through the passes of a rolling mill, bending the web and the flanges on one side of the web and bringing each 50 bent flange into substantially the same plane as the adjoining bent web portion in some of said passes, reducing the area of the bent shape in other of the passes, straightening 55

the bent web and bringing the bent flanges and adjoining bent web portions into the 65 same plane in later passes and bending the flanges on the opposite side of said web inwardly toward each other into hook form in some of said later passes.

8. The method of rolling flanged shapes 70 consisting in subjecting a heated blank having oppositely extending flanges along the marginal edges of a connecting web to the action of the passes of a rolling mill, bending the flanges on one side of said web each 75 into the plane of the web while maintaining the flanges on the opposite side without material change in the position thereof relative to the web in some of said passes, then reducing the cross sectional area of the so 80 formed blank and upsetting the flange portions on one side of the web in other passes and bending the upset flange portions on one side of the web inwardly to form inwardly extending oppositely facing hooks 85 in a later pass.

9. The method of rolling flanged shapes consisting in subjecting a heated blank having oppositely extending flanges on the marginal edges of a connecting web portion to 90 the action of the passes of a rolling mill, bending the web into planes at an angle to each other and the flanges on one side of the web each into the plane of the adjoining bent portion of the web in some of said 95 passes, upsetting the flanges on the opposite side of the web in at least one later pass and then straightening the bent web to bring the web and flanges on one side of the web into the same plane and bend the upset 100 flanges on the opposite side of said web in other of the passes.

10. The method of rolling flanged shapes consisting in subjecting a heated blank having oppositely extending flanges on the marginal edges of a connecting web portion to the action of the passes of a rolling mill, bending the web into planes at an angle to each other and the flanges on one side of the web each into the plane of the adjoining 110 bent portion of the web in some of said passes, upsetting the flanges on the opposite side of the web and reducing the area of the blank in at least one later pass and then straightening the bent web to bring the web 115 and flanges on one side of the web into the same plane and bend the upset flanges on the opposite side of said web in other of the passes.

In testimony whereof, I have hereunto set 120 my hand.

EDWIN E. SLICK.
